(57) **CLAIM**

The ornamental design for a straightening iron, as shown and described.

DESCRIPTION

FIG. 1 is a top, right side perspective view of a new, original and ornamental design for a straightening iron, the straightening iron depicted in a closed position;

FIG. 2 is a right side elevation view of FIG. 1;

FIG. 3 is a left side elevation view of FIG. 1;

FIG. 4 is a front elevation of FIG. 1;

FIG. 5 is a rear elevation view of FIG. 1;

FIG. 6 is a top plan view of FIG. 1;

FIG. 7 is a bottom plan view of FIG. 1;

FIG. 8 is a top, right side perspective view of the straightening iron in an open position;

FIG. 9 is a right side elevation view of FIG. 8;

FIG. 10 is a left side elevation view of FIG. 8;

FIG. 11 is a front elevation of FIG. 8;

FIG. 12 is a rear elevation view of FIG. 8;

FIG. 13 is a top plan view of FIG. 8; and,

FIG. 14 is a bottom plan view of FIG. 8.

The broken lines in the drawings depict portions of the straightening iron that form no part of the claimed design.

1 Claim, 11 Drawing Sheets
